INTERCHANGEABLE FOUNTAIN MARKING
PENHenry Oelbaum, Cranston, R. I., assignor to
Harold Hassenfeld, Providence, R. I.

Application July 24, 1936, Serial No. 92,281

5 Claims. (Cl. 120—111)

This invention relates to new and useful improvements in an interchangeable fountain marking pen.

The invention has for an object the construction of a marking pen which is characterized by a good control of the fluid supply.

Specifically, the invention contemplates the construction of a marking pen which is characterized by a strip of stiff metal having a pair of spaced arms joined at the bottom ends, and a transverse curved portion formed with slits for the passage of ink or paint and adapted to be associated with a corrugated supply holding strip, and arranged with the upper portions of the said strip of metal being curved longitudinally forming a tubular double split shank which may engage a receiving holder.

Furthermore, the invention contemplates arranging the corrugated strip with its upper edge portions curved longitudinally forming a tubular single split shank engaged within said tubular split shank and adapted to frictionally maintain its position when the pen is engaged in a pen holder.

Still further the invention proposes an arrangement whereby the corrugated strip may be positively held in various adjusted positions from the transverse curved portion of the outer strip of material, to control the flow of the ink.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a fountain marking pen upon a holder and constructed according to this invention.

Fig. 2 is a perspective enlarged view of the marking pen shown in Fig. 1, but illustrated per se.

Fig. 3 is an elevational view of Fig. 2.

Fig. 4 is a bottom view of Fig. 2.

Fig. 5 is a perspective view of the interior corrugated strip.

Fig. 6 is a view similar to Fig. 3 but illustrating another embodiment of the invention.

Fig. 7 is a sectional view taken on the line 7—7 of Fig. 6

The fountain marking pen, according to this invention, comprises an outer casing consisting of a strip of stiff metal having a pair of spaced arms 10 and 11 joined at their bottom ends in a trans-

verse curved portion 12. This curved portion is formed with a plurality of slits 13 for the passage of ink or paint from between the arms, outwards. The upper portions of the arms 10 and 11 are longitudinally curved forming curved portions 10^a and 11^a respectively which together comprise a tubular double split shank.

A corrugated strip of stiff material 14 is arranged between the arms 10 and 11 and has its upper edge portions 14^a curved longitudinally 10 forming a tubular single split shank 14'. This shank 14' is adapted to engage coaxially within the shank 10^a, 11^a and frictionally maintain its position when the fountain marking pen is within a holder. In Fig. 1 a holder 17 is illustrated 15 formed with a circular recess 18 at the bottom end adapted to receive the shanks of the marking pen. In order to engage the shanks into the opening 18 it is necessary that they be forced together and the pressure between these parts provides the friction, as previously pointed out.

In Figs. 6 and 7 a modified form of the invention has been disclosed which differs from the prior form in several respects. In the first place the arms 10' and 11' are relatively much wider than 25 the arms 10 and 11. Between these arms there is a strip 14'' which is of substantially the same width as the arms. At the upper portions the side arms 10' and 11' are curved longitudinally forming portions 10^a and 11^a comprising a tubular 30 double split shank adapted to engage an opening in a holder.

The upper portion of the corrugated strip 14'' has its edges longitudinally curved forming a tubular single split shank 14'. A headed stud 19 35 is mounted on the inner wall of one of the sections of the outer shank and engages through the said single slit of the inner shank. This headed stud has a friction collar 20 mounted thereon which is adapted to frictionally engage the edges of the 40 slit and so frictionally hold the inner and outer shanks relative to each other.

In this form of the invention it is manually necessary to shift the shanks relative to each other into desired positions, even while the marking 45 pen is not mounted in a pen holder. Furthermore, when the sections of the shanks are forced together when engaging the marking pen into a holder, additional frictional resistance will be created which assists in holding the corrugated 50 strip at a pre-determined position.

While I have illustrated and described the preferred embodiments of my invention, it is to be understood that I do not limit myself to the precise constructions herein disclosed and the right 55

is reserved to all changes and modifications coming within the scope of the invention as defined in the appended claims.

Having thus described my invention, what I claim as new, and desire to secure by United States Letters Patent is:—

1. An interchangeable fountain marking pen comprising an outer casing consisting of a strip of stiff material having a pair of spaced arms joined at the bottom ends with a transverse curved portion formed with slits for the passage of ink or paint, the upper portion of said arms being longitudinally curved forming a tubular double split shank, and a corrugated strip of stiff material between said arms and having its upper edge portions longitudinally curved forming a tubular single split shank disposed within said shank for frictional association, when the sections of the outer shank are forced together 20 into a pen holder.

2. An interchangeable fountain marking pen comprising an outer casing consisting of a strip of stiff material having a pair of spaced arms joined at the bottom ends with a transverse curved portion formed with slits for the passage of ink or paint, the upper portion of said arms being longitudinally curved forming a tubular double split shank, and a corrugated strip of stiff material between said arms and having its upper edge portions longitudinally curved forming a tubular single split shank disposed within said shank for frictional association, when the sections of the outer shank are forced together into a pen holder, the lower flat portions of said spaced arms being relatively much wider than the curved tubular portions.

3. An interchangeable fountain marking pen comprising an outer casing consisting of a strip of stiff material having a pair of spaced arms joined at the bottom ends with a transverse curved portion formed with slits for the passage of ink or paint, the upper portion of said arms being longitudinally curved forming a tubular double split shank, and a corrugated strip of stiff material between said arms and having its upper edge portions longitudinally curved forming

a tubular single split shank disposed within said shank for frictional association, when the sections of the outer shank are forced together into a pen holder, the single split of the inner shank being out of line with either one of the splits in 5 the outer shank.

4. An interchangeable fountain marking pen comprising an outer casing consisting of a strip of stiff material having a pair of spaced arms joined at the bottom ends with a transverse curved portion formed with slits for the passage of ink or paint, the upper portion of said arms being longitudinally curved forming a tubular double split shank, a corrugated strip of stiff material between said arms and having its upper edge portions longitudinally curved forming a tubular single split shank disposed within said shank for frictional association, when the sections of the outer shank are forced together into a pen holder, and a headed stud mounted on 20 the inner wall of one of the sections of said outer shank and engaging through said single split for frictionally engaging the edges thereof and assisting in maintaining fixed positions.

5. An interchangeable fountain marking pen 25 comprising an outer casing consisting of a strip of stiff material having a pair of spaced arms joined at the bottom ends with a transverse curved portion formed with slits for the passage of ink or paint, the upper portion of said arms 30 being longitudinally curved forming a tubular double split shank, a corrugated strip of stiff material between said arms and having its upper edge portions longitudinally curved forming a tubular single split shank disposed within said 35 shank for frictional association, when the sections of the outer shank are forced together into a pen holder, and a headed stud mounted on the inner wall of one of the sections of said outer shank and engaging through said single split 40 for frictionally engaging the edges thereof and assisting in maintaining fixed positions, said headed stud having a resilient collar mounted thereon, the sides of which engage the edges of said single split.

HENRY OELBAUM. 45
